Attorney

W. H. Tammel

UNITED STATES PATENT OFFICE.

ELIZABETH E. BRINSER, OF ELIZABETHTOWN, PENNSYLVANIA.

AUTOMATIC PATTERN STAB.

Application filed March 31, 1928. Serial No. 266,369.

In my Patent, No. 1,646,744, granted October 25, 1927, for automatic pattern stabs, I have shown several forms of devices for securing the stabs to a pattern. The present invention is in the nature of an improvement 5 on the element for securing the device to a pattern.

The invention consists of a stab having both ends blunt pointed, one end having at 10 its base a laterally extended and preferably circular flange made integral therewith, and the other end having at its base a groove in which is upset and clinched a securing element, also preferably circular, and having a 15 down-turned rim and a countersunk perforated crown, the securing element being slipped over the grooved end and its rim sunk in the pattern and its countersunk crown flattened out upon the surface of the pattern and 20 the rim or edge of the hole in the countersunk portion engaging the groove in the end, as I will proceed now to explain more fully and finally claim.

In the accompanying drawings illustrating 25 the invention, in the several figures of which like parts are similarly designated, Figure 1 is a top plan view of a pattern for a shoe upper part, with three of my stabs in position. Fig. 2 is an enlarged cross section 30 on line 2—2 of Fig. 1, of the set stab and a portion of the pattern. Fig. 3 is an elevation, and Fig. 4 is a plan view of parts of the stab, on the same scale as Fig. 2. Fig. 5 is a top plan view and Fig. 6 is a cross section of 35 the securing element, also on the scale shown in Fig. 2.

The pattern 1 may be for any of the parts of a shoe, but is here shown as for the vamp, and as usual has the metal binding 2. At any 40 desired positions are placed the stabs 3.

As shown, the stab may have a body portion 4 of cylindrical form, having both of its ends 5 and 6 blunt-pointed so as not to mar or deface the leather to be cut as the pattern is 45 moved into position on the material to be marked and cut and yet leave a mark thereon to guide the stitcher in properly uniting the parts of a shoe or other article. At the base of one of the blunt points is a laterally ex- 50 tended flange 7, preferably circular and made integral with the body, although it may be attached thereto. At the base of the other blunt-pointed end of the body is a circumferential groove 8 adapted to receive and 55 fixedly engage the securing element 9.

The securing element 9 is made with a

crown 10 having a down-turned rim flange 11, the crown 10 having a central countersink 12 with a hole 13 in it.

The pattern is perforated for the reception 60 of the body of the stab, with the grooved end of the body projecting beyond the surface of the pattern, and then the securing element is applied to this grooved end by forcing its perforated countersink over the blunt end 65 and its rim sunk in the pattern until the countersunk crown is flattened out and the rim of the hole therein is forced into engagement with the groove 8, as shown in Fig. 2.

By the means described the securing element 70 takes fast hold not only on the body of the stab but also in the material of the pattern, and the union of stab and pattern is thereby firmly and smoothly effected, without any edges projecting from the securing 75 element.

The stab body has both ends alike, and these 80 ends project from opposite sides of the pattern, so that the pattern equipped with my stabs may be used reversely for stabbing purposes in cutting and marking both right and left shoe portions.

The invention is not limited to use on 85 leather nor on shoe parts regardless of their material, and is applicable, also, in the manufacture of purses, pocket-books, bags and other containers made up of parts which are to be stitched together.

By means of a stab constructed as described, the correct marking of a pattern is 90 absolutely ensured, because the stabs are fixedly applied to the pattern and extend in the same plane from both sides. When the pattern is placed on the material the operator simply presses it sufficiently to make the correct impression. Obviously the operator must apply sufficient pressure to the pattern when cutting to prevent it from slipping, and with 95 slightly additional pressure, he can make the impression on the material. Because of this 100 mode of operation, I have designated my device as an automatic pattern stab.

The securing element 9 may be varied in detail within the principle of my invention and the scope of the claims following. 105

What I claim is:—

1. A pattern stab, having a body provided with a circumferentially grooved blunt end and adapted to be applied to a pattern with the end projecting from one of the sides of the 110 pattern, and a securing element having a crown provided with a countersunk and per-

forated portion to engage the groove in said blunt end and clinched therein by flattening the countersunk crown on the pattern.

2. A pattern stab, having a body provided with blunt ends, one of said ends having a circumferential groove and the other end having a retaining flange, and a securing element composed of a crown having a central perforated countersink and a down-turned rim.

10 3. A pattern stab, having a body provided with blunt ends, one of said ends having a circumferential groove and the other end having a retaining flange, and a securing ele-

ment composed of a crown having a central perforated countersink and a down-turned rim, combined with a pattern in which the body is placed with its blunt ends projecting from opposite sides, the securing element being applied to the grooved end by its countersink and its rim sunk in the pattern by flattening the crown about the grooved end and into engagement therewith and the pattern.

In testimony whereof I have hereunto set my hand this 30th day of March A. D. 1928.

ELIZABETH E. BRINSER.
